(No Model.)

G. D. HUNTER.
CRIMPER FOR CARTRIDGE SHELLS.

No. 449,537.

Patented Mar. 31, 1891.

Inventor:

George D. Hunter.

UNITED STATES PATENT OFFICE

GEORGE D. HUNTER, OF AUBURN PARK, ILLINOIS.

CRIMPER FOR CARTRIDGE-SHELLS.

SPECIFICATION forming part of Letters Patent No. 449,537, dated March 31, 1891.

Application filed October 3, 1890. Serial No. 366,989. (No model.)

To all whom it may concern:

Be it known that I, GEORGE D. HUNTER, a citizen of the United States, residing at Auburn Park, in the county of Cook and State 5 of Illinois, have invented certain new and useful Improvements in Crimpers for Cartridge-Shells; and I do hereby declare the following to be a full, clear, and exact description of the invention, such as will enable others skilled in 10 the art to which it appertains to make and use the same.

My invention relates generally to devices for closing or crimping the outer or front ends of the paper or pasteboard cartridge-shells 15 used in breech-loading shotguns, and particularly to improvements in this class of devices which render them more durable than usual and effective in operation or capable of smoothly and perfectly closing the ends of 20 said cartridge-shells after the powder, shot, and wads have been placed in their respective positions therein; and it consists in the peculiarities of construction and arrangement or combination of parts and features 25 hereinafter fully disclosed in the description, drawings, and claims.

The object of my invention is to provide a crimpler for cartridge-shells which will be more durable or last longer than those usually 30 employed, which will avoid the great amount of friction usually pertaining to crimpers manufactured wholly of brass or other metal, which will lessen the usual tendency to tear or roughen the ends of the paper shells of 35 cartridges while they are being inturned or crimped, which will be capable of employment in fixed or portable machines for loading and crimping cartridge-shells, in separate crimping-machines, in separate machines for 40 cutting and crimping cartridge-shells which may have been filled by hand, or in a machine, for instance, of the character of that disclosed in the Letters Patent granted to me May 29, 1888, No. 383,529, and which will be 45 simple in construction and cheap to manufacture. This object is accomplished by the improved construction and arrangement or combination of the parts and features of this invention, which is embodied in slightly different forms or constructions, as shown in the 50 accompanying drawings, constituting part of this specification, in which the same refer-

ence-numerals indicate the same or corresponding parts, and in which—

Figure 1 represents a section of one of my 55 improved crimpers for cartridge-shells and of the glass crimping-disk removed therefrom; Fig. 2, front views of complete crimpers, showing the glass crimping-disks held in place in the chambers of the holders by and without 60 the inturned flange on the front end of the latter; Fig. 3, rear views of the glass crimping-disk and the wheel for revolving the crimpler shown in Fig. 1; Fig. 4, partly-sectional and front views of a modified form or 65 construction of my improved crimpler; Fig. 5, sectional and front views of another slightly-modified construction of the same, and Fig. 6 sectional and front views of another slightly-modified form of construction of the same. 70

In the drawings, the numeral 1 indicates my improved crimpler, which, as shown in Fig. 1 of the drawings, is composed of the holder 2, having the recess or chamber 3 formed in its front end or face and the pinion 4 on its rear 75 end, centrally of which is formed the axial recess 5 for receiving a short shaft or bolt for supporting said crimpler while it is being revolved—as, for instance, by the means disclosed in my above-mentioned patent. In the 80 recess or chamber 3 of the holder 2 is fitted the glass crimping-disk 6, which has a body portion 7 of a shape corresponding to the interior of said chamber and is seated or embedded therein in a layer of plaster-of-paris, 85 white lead, or other suitable cement 8. On or in the rear surface of this glass crimping-disk are formed the small ribs or grooves 9, which are pressed into the cement for preventing said disk from turning and for holding the same firmly in place in all directions. 90 However, the attainment of these results may be assisted by the inturned flange 10 at the front end of the holder 2, which will prevent all possibility of outward or forward movement of said disk. The front or operative surface of this glass crimping-disk is formed with the raised center 11, the rim 12, the intermediate annular groove 13, and the bosses or slightly-raised projections 14 near the bottom of said groove. 95

A cartridge-shell while being closed or crimped is required to be firmly supported at its rear end and prevented from turning. 100

A device for accomplishing this result may be the same as the chuck-cups or shell-rests used in connection with the ordinary cartridge-crimpers, or it may be the same as the adjustable chuck-wheel disclosed in my above-named patent, which is capable of receiving and firmly holding the rear ends of cartridges of various sizes.

In the modified forms or constructions of my improved crimper shown in Figs. 4 and 5 of the drawings the glass crimping-disks 6 are substantially the same as the one already described. The holders 2, however, are different from the one above described, that shown in Fig. 4 being made in the form of a cap or collar, which is interiorly screw-threaded and enlarged along its rear portion, which is contracted along its front portion for forming the recess or chamber 3 for the glass crimping-disk 6, and into which at its rear portion is inserted the exteriorly-screw-threaded and enlarged shaft-head 15, which fits removably therein and is formed with a flat front face opposite the flat rear face of said glass disk. Intermediate of the flat rear face of this disk and the flat front face of this shaft-head may be placed the annular soft-rubber plate 16, which will form a yielding seat for said glass disk and prevent its breakage from jar or frictional contact with cartridge-shells while they are being crimped; also, this disk is placed in the recess or chamber 3 of the holder 2 by being passed forwardly through the opening in the enlarged rear portion thereof, after which it is firmly held in place by its rim 12 resting against the inturned flange 10 on the front end of said holder, and by the rubber plate 16, when used, and the enlarged shaft-head 15 pressing against its rear face. The annular channel 17 is formed in the inner surface of the holder 2 for the purpose of facilitating the formation of its internal screw-thread. The holder 2 for the glass crimping-disk 6 (shown in Fig. 5 of the drawings) is of substantially the same construction as the holder shown in Fig. 1, the only differences being that it has no inturned flange on its front end, but may have, and that it has no pinion for effecting its revolution, but instead is formed with the interiorly-screw-threaded neck 18, into which is fitted an exteriorly-screw-threaded shaft-head like that shown in Fig. 4.

In the additional slightly-modified form or construction of my improved crimper shown in Fig. 6 of the drawings the only change resides in the fact that the holder 2 is formed integrally with the shaft-head 15.

It will be evident from the foregoing that the gist of my invention resides in the incasement of a glass crimping-disk of the construction described in a suitable metallic holder, which can be accomplished in many different ways; that the employment of this glass crimping-disk will obviate all the frictional disadvantages that are incident to the use of brass and other wholly metallic crimpers, in which

the bosses or slightly-raised projections wear out in a very short time and roughen the paper from which the shells are made; that this glass disk will make smoother crimps in shells than when wholly metallic crimpers are employed; that the seating or embedding of said glass disk in cement holds it firmly in place, insures it against breakage, affords it a true or level seat in its recess or chamber in the holder, and permits the outside of the latter to be turned true after said disk has been placed in operative position, whereas when the entire crimper is made of metal it is generally cast and then swaged to the desired size, which cannot be done with certainty or accuracy owing to the roughness and shrinkage of the metal, and that a crimper provided with this glass crimping-disk will turn over or crimp the dry paper shells of cartridges without any twisting strain thereon whatever and will operate with less friction than metallic crimpers, and consequently require less power for its operation.

Having thus fully described the construction and arrangement or combination of the parts and features of my invention, its advantages and operation, what I claim as new is—

1. A crimper for cartridge-shells, provided with a glass crimping-disk substantially as described.

2. A crimper for cartridge-shells, provided with a holder having a recess or chamber in its front end or face and a glass crimping-disk secured in said chamber, substantially as described.

3. A crimper for cartridge-shells, provided with a holder having a recess or chamber in its front end or face, a layer of cement therein, and a glass crimping-disk seated or embedded in said cement, substantially as described.

4. A crimper for cartridge-shells, provided with a holder having a recess or chamber in its front end or face, a layer of cement therein, and a glass crimping-disk seated or embedded in said cement and formed with a series of small ribs or grooves on or in its rear surface, substantially as and for the purpose described.

5. A crimper for cartridge-shells, provided with a holder having a recess or chamber in its front end or face, an inturned flange at its front end, and a glass crimping-disk within said chamber, substantially as described.

6. A crimper for cartridge-shells, provided with a holder having a recess or chamber in its front end or face, a layer of cement therein, and a glass crimping-disk seated or embedded in said cement and formed with a series of small ribs or grooves on or in its rear surface and an inturned flange at its front end, substantially as and for the purpose described.

7. A crimper for cartridge-shells, provided with a holder having a recess or chamber in its front end or face, an inturned flange at its front end, a glass crimping-disk within said chamber, an interiorly-screw-threaded

rear portion, and an exteriorly-screw-threaded and removable shaft-head, substantially as described.

8. A crimper for cartridge-shells, provided with a holder having a recess or chamber in its front end or face, an inturned flange at its front end, a glass crimping-disk within said chamber, an interiorly-screw-threaded rear portion, an exteriorly-screw-threaded shaft-head, and a rubber plate arranged intermediate of the rear face of said glass disk and the front face of said shaft-head, substantially as described.

9. A crimper for cartridge-shells, provided with a holder having a recess or chamber in its front end or face, an inturned flange at its

front end, a glass crimping-disk within said chamber, an interiorly-screw-threaded rear portion, an exteriorly-screw-threaded shaft-head, a rubber plate arranged intermediate of the rear face of said glass disk and the front face of said shaft-head, and an annular channel formed in the inner surface of said holder, substantially as and for the purpose described. 25

In testimony whereof I affix my signature in presence of two witnesses.

GEORGE D. HUNTER.
